UNITED STATES PATENT OFFICE.

JOHN LOOMIS WALKER, OF CHICAGO, ILLINOIS, ASSIGNOR TO PHEOLL MANUFACTURING COMPANY, OF CHICAGO, ILLINOIS, A CORPORATION OF ILLINOIS.

APPARATUS FOR SHAPING METAL PIECES.

Application filed May 13, 1922. Serial No. 560,523.

While my invention relates more particularly to the trimming of the heads of bolts and cap-screws, it is not necessarily limited to such use. Among the objects of this invention are to shave from a metal part an undesired portion of the metal in such a manner as to leave the surface of the metal part substantially smooth; to provide a new method of shaping metal parts so that the amount of tearing of the metal will be reduced to a minimum; to provide mechanism for removing from the surface of the metal parts, in an economical manner, any irregularities, so that the surface of the metal will be left substantially smooth; to provide novel mechanism for accomplishing the foregoing and other functions; and such further objects, advantages and capabilities as will later more fully appear.

My invention further resides in the combination, construction and arrangement of parts illustrated in the accompanying drawings, and while I have shown therein a preferred embodiment I desire the same to be understood as illustrative only and not as limiting my invention.

In the accompanying drawings:

Fig. 1 is a plan view of a machine embodying the principles of my invention.

Fig. 2 is an elevation of a portion of the actuating mechanism for a metal piece.

Fig. 3 is a fragmentary longitudinal vertical section substantially along the plane indicated by the line 3—3, Fig. 1.

Fig. 4 is a similar section showing the parts in another operative position.

Fig. 5 is an other similar section showing the parts in a third operative position.

Fig. 6 is an enlarged fragmentary section showing the construction and arrangement of the die members.

Fig. 7 is a view similar to Fig. 6 showing a metal piece in a further advanced stage of its passage through the die members.

Fig. 8 is a section similar to Figs. 6 and 7, but showing the chip remover in the act of passing down between the dies.

Fig. 9 is a section at right angles to Fig. 8.

Fig. 10 is a transverse section through the machine substantially along the plane indicated by the line 10—10, Fig. 5.

Fig. 11 is a fragmentary sectional elevation of the fly wheel and associated parts, to illustrate the action of certain ones thereof.

Referring more in detail to the drawings, numeral 1 designates the frame of the machine in which is mounted a power shaft 2, carrying, in the present instance, a fly wheel 3, which fly wheel is provided with a cam 4 for a purpose to be disclosed later. The frame 1 is provided with slide-ways 6 in which operates the slide 5 carrying the trimming punch 7 within which slides the ejector rod 7^a, and in front of which the blank 8 is positioned by mechanism not shown. Ejector rod 7^a is easily removable and replaceable so that rods of different lengths may be used, the particular length used being dependent upon the length of the blank 8 being trimmed. A pair of die members 9 and 10 are carried by one end of the frame 1 and have mounted therein removable and interchangeable die plates 11 and 12. A cam 13 is carried by power shaft 2 and rotates therewith in the direction shown by the arrow. This cam engages roller 14 carried by shaft 15 mounted in the slide 5. Also carried by the power shaft 2 is a cam 16 which engages a roller 17 carried by a stub-shaft 18 mounted in a projection 19 from the slide 5. It will be clear from this that cam 13 actuates the slide 5 in a forward direction to force the cap-screw blank 8 through the die-plates 11 and 12 and that cam 16 engaging roller 17 returns the slide to initial position.

The opening in die-plate 12 has its faces parallel with those in die-plate 11, but it is slightly smaller than the opening in plate 11 so that as the blank 8 is pushed therethrough a thin shaving is taken from each of the faces of the cap-screw head, thereby trimming off any unevenness left after passing it through the first die-plate, the latter effecting the rough cutting or shearing of the head. It was found during the development of this machine that, if means were not provided for removal of the chips between the two die plates, the space would shortly fill up and cause roughening of the surface of the bolt or cap-screw heads as the same pass through the second die-plate. There was also a tendency to injure the cutting edge of the second die-plate and, for the foregoing reasons, mechanism was provided for the removal of the chips between the two plates, before the passage of a bolt or capscrew through the second die member. To accomplish this function, a chip ejector 20 is

5 moved transversely of the machine between the die members 9 and 10, preferably in a downward direction. This is accomplished by the action of lever 21 pivoted on the frame 1 at 22 and carrying a roller 23 which normally rides on shaft 24 carried by slide 5. This shaft 24 has at its end an enlargement 25 which engages the roller 23 and causes lever 21 to be turned on its pivot to 10 force the chip ejector 20 through the space between the die members, thus causing any chips clinging to die plate 12 to be ejected before the next blank is forced through the dies.

15 Starting with the cam 13 in the position shown in Fig. 3, the slide 5 is fully withdrawn to what may be called initial position and the roller 14 contacts with cam 13 at point A. From position A to position B the 20 slide is advanced rapidly by the cam 13, while from B to C the advance is much more slow. From C to D there is hesitation or 25 substantially a pause in the forward movement of the slide to permit the metal of the cap-screw blank to reset, the purpose of which is to prevent tearing of the metal near the underside of the head as the last portion of the head goes through the first die, which takes place while the cam is traveling from the position D to the position E in 30 contact with the roller 14, that part of the cam 13 between E and F causing the blank to pass through the second die. Bolt and cap-screw makers have found that in pushing a metal piece through a die, with a substantially constant motion, the metal which goes through the die last has a tendency to tear very materially so that when the metal part emerges from the machine the 35 surfaces thereof formed by the die during the latter part of its cutting action, are almost universally rough. Various expedients have been adopted in an effort to secure bolts and cap-screws having heads with smooth 40 surfaces. It is believed that no machine has been produced prior to the presented invention which will accomplish this result and, certainly, none has been produced which will 45 accomplish the same in so economical a manner, since the present machine requires but a single operation, whereas former methods of operation required the passage of the metal piece through a plurality of machines successively or through a single machine 50 having other inherent defects.

55 After the head has been trimmed as described above and the metal piece has reached the position shown in Fig. 7, cam 4 strikes roller 26 mounted on the inner end 60 of lever 27 and causes this to be turned quickly about its pivot 28 so that the end of screw 29, carried by the end of arm 30, strikes the end 31 of lever or crank arm 32 a sharp blow. This in turn strikes the head 33 of 65 ejector rod 7^a so as to throw the blank 8

outwardly and leave the trimming punch 7 empty for the reception of another blank. The parts are shown in Fig. 5 in position for this operation to take place, and it will be seen from this figure that when the fly 70 wheel 3 turns a short distance further cam 4 will strike roller 26 as described above. After the ejection of the blank 8, the machine is ready for the retraction of the slide 5, which begins when a point corresponding 75 approximately to position G on cam 16 strikes roller 17. This action continues until the point H on cam 16 passes said roller whereupon the slide is in position to begin again its forward movement, as soon as cam 80 13 comes into contact with roller 14.

85 Inasmuch as the mechanism for placing the blanks 8 in position between the trimming punch 7 and the die member 9 forms no part of the present invention, the construction thereof is neither disclosed nor claimed herein.

90 Crank arm 32 is supported on a pivot member 35, the ends of which extend into a boss 36 extending around three sides of the aperture in slide member 5 within which the roller 14 is mounted. This crank arm normally occupies the position shown in Fig. 3, and a spring 33^a holds ejector rod 7^a normally 95 retracted, but yields to permit the blank to be ejected from trimming punch 7.

100 When the trimming motion has been completed as shown in Fig. 5, crank arm 32 is in such position below the adjustable screw 29 that the lower end of said screw will 105 strike the end 31 of arm 32, thus giving to ejector rod 7^a the quick action referred to above for throwing the blank 8 out of trimming punch 7.

110 It is of course understood that the specific description of structure and method set forth above may be departed from without departing from the spirit of my invention as set forth in this specification and the appended claims.

115 Having now described my invention, I claim:—

120 1. In a metal shaping machine, a pair of aligned, spaced dies through which a formed piece of metal may be passed, a punch movable through said dies for successively moving the metal piece therethrough, means for causing a pause in passing the metal through said machine to prevent tearing of the metal, and means movable intermittently through the space between the dies to remove any chips lodging therein.

125 2. In a metal shaping machine, a pair of aligned, spaced dies through which a formed piece of metal may be passed, means for forcing such a piece of metal through the dies, and means movable intermittently through the space between the dies to remove any chips lodging therein.

130 3. In a metal shaping machine, a pair of

- aligned, spaced dies through which formed pieces of metal may be passed intermittently, means for forcing such pieces of metal through the dies, the second die being slightly smaller than the first, and chip removing means passing through the space between the dies transversely of the machine to remove any chips therefrom before a piece of metal is forced through the second die.
4. In a metal shaping machine, a pair of axially aligned, spaced die members, removable die plates secured to the die members, and chip removing means passing through the space between the dies to remove therefrom any chips before the passage of a metal piece through the second die.
5. In a metal shaping machine, a pair of axially aligned, spaced die members, a removable die plate secured to each die member, chip removing means passing through the space between the dies to remove therefrom any chips before the passage of a metal piece through the second die, and means for passing a metal piece through the first die with a hesitating motion and then continuing the passage through the dies.
6. In a metal working machine, a die, holding means for a metal part to be operated on, means to advance the holding means to force the metal part through the die, said advancing means including a cam shaped to cause the metal part to pass partly through the die and then hesitate before completing its passage and then continue to force the part completely through the die to complete said passage before acting on a succeeding metal part.
7. In a metal working machine, a die, holding means for a metal part to be operated on, means to advance the holding means to force the metal part through the die, said advancing means including a cam shaped to cause the metal part to pass partly through the die and then hesitate before completing its passage, said mechanism also including a cam to cause retraction of the holding means after the metal part has been completely forced through the die.

In witness whereof, I hereunto subscribe my name to this specification.

JOHN LOOMIS WALKER.
